UNITED STATES PATENT OFFICE

ADELE SMITHLINE, OF NEW YORK, N. Y., ASSIGNOR TO ASSOCIATED MERCHANTISING CORPORATION, OF NEW YORK, N. Y., A CORPORATION OF NEW JERSEY

DESIGN FOR AN ENSEMBLE DRESS

Application filed December 28, 1931. Serial No. 42,263. Term of patent 3½ years.

To all whom it may concern:

Be it known that I, ADELE SMITHLINE, a citizen of the United States, and a resident of New York, borough of Manhattan, in the county of New York and State of New York, have invented the new, original, and ornamental Design for an Ensemble Dress, of which the following is a specification.

Reference is had to the accompanying drawings, forming part thereof, wherein—

I claim:

The ornamental design for an ensemble dress substantially as shown.

ADELE SMITHLINE.
